UNITED STATES PATENT OFFICE.

HERMAN MENTEN, OF NEW YORK, N. Y.

SAFETY GAS-BURNER.

1,109,537.

Specification of Letters Patent.

Patented Sept. 1, 1914.

Application filed July 28, 1911. Serial No. 641,163.

To all whom it may concern:

Be it known that I, HERMAN MENTEN, a citizen of the United States; residing in New York, county of Queens, and State of New York, with post-office address at 430 Sherman street, Astoria, New York, N. Y., have invented certain new and useful Improvements in Safety Gas-Burners, of which the following is a specification.

This invention relates to safety gas burners and especially to gas burners for stoves or other devices in which the gas is used for heating.

The invention is particularly applicable to burners in which the flame is concealed from view, though it is also applicable to any other type of gas burner.

The primary object of the invention is to provide a gas burner of such construction that when the need for the gas flame ceases the flow of gas will be automatically cut off and a signal operated to indicate that the gas is no longer required.

In the accompanying drawings I have illustrated two embodiments of my invention which differ in respect to the character of the signal employed.

In the drawings: Figure 1 is a view principally in vertical longitudinal section of improved gas burner provided with a mechanically operated bell to serve as a signal. Fig. 2 is a plan view of the structure shown in Fig. 1. Fig. 3 is a perspective view of an electric bell connected with the burner to serve as a signal.

I have illustrated my improved burner as applied to a heating stove and have shown a conventional arrangement of parts for such a burner together with the novel elements which in combination comprise my invention.

In the drawings, 1 designates a gas chamber of suitable form having perforations in the top where the gas is ignited. The gas chamber is of the usual annular form and in the center is a guide 2 through which passes a vertical standard 3 which carries on its upper end a spider 4 upon which any vessel or other body to be heated must be placed. The lower end of the standard 3 rests upon one arm of a bell crank lever 5 the other arm of which is connected by a link 6 with a second bell crank lever 7 which operates a valve 8 which controls the flow of gas to the chamber 1. A weight 9 is attached to one arm

of the bell crank lever 7 and rests, as shown in Fig. 1, upon an arm 10 which controls the mechanism of the signal bell 11. A small bore tube 12 extends from the valve 8 to the burner and serves as a pilot light so long as the cut off valve 13 is open.

The operation of the safety gas burner above described will be readily understood from the description and drawings. The parts are shown in Figs. 1 and 2 in the position in which they are left immediately after removing from the burner the body which has been receiving heat. The weight 9 acting upon the bell crank lever 7 has raised the spider 4 and has itself descended upon the arm 10 upon the bell 11. The movement of the bell crank lever 7 under the action of the weight has closed the valve 8 and cut off the supply of gas to the chamber 1, and has also caused the bell 11 to begin ringing, thus calling attention to the fact that the supply of gas to the burner has been cut off but the pilot light is still burning. If the burner is to be used again in a few moments the person in charge will simply swing the weight 9 to one side so as to release the arm 10 and stop the ringing of the bell 11. If the burner is not to be used in the immediate future the person in charge will not only stop the ringing of the bell by swinging the weight 9 off the arm 10 but will use the valve 13 to cut off the flow of gas to the pilot light.

The next time a body to be heated is placed on the spider 4 the weight of the body will depress the spider thereby operating both crank levers and opening the valve 8. The movement of the bell crank lever 7 when the valve 8 opens will raise the weight 9 so that it will swing into position above the arm 10 in readiness to set the bell in action as soon as the body to be heated is removed from the burner.

In Fig. 3 I have shown the adaptation of an electric bell to the safety burner. Instead of the mechanically operated bell 11 I mount beneath the cut off valve 13 a supporting bracket 14 for an ordinary push button circuit closer 15 which is actuated by means of a hinged arm 16 upon which the weight 9 descends when the body to be heated is removed from the burner. The wires 17 comprising the circuit connecting the circuit closer 15 with the electric bell 18 are carried to the push button through suitable conduits 19 to any desired construction.

Having thus described my invention what I claim as new and desire to secure by Letters Patent is:

The combination of a gas burner, a pipe 5 conducting the gas thereto, a manually operatable valve in said pipe, a second valve in said pipe between said first mentioned valve and said burner, a movable vessel support carried by said gas burner, a connection between said support and said second valve adapted to open said valve upon depression of said support, a projecting arm carried by said valve and movable upon the actuation of said valve by said support, a 15 signal device attached to the rotatable por-

tion of the first mentioned valve, said signal device having an operating arm which is brought into the path of movement of the projecting arm of said second valve when said first valve is turned to opened position, and means for closing said second valve when said vessel support is free of weight.

In testimony whereof, I have signed my name hereto in the presence of witnesses. 25

HERMAN MENTEN.
